UNITED STATES PATENT OFFICE.

BENJAMIN S. WARREN, OF DETROIT, MICHIGAN, ASSIGNOR TO C. B. HUTCHINS & SONS, OF DETROIT, MICHIGAN, A CORPORATION OF MICHIGAN.

CAR-ROOF.

No. 905,982.

Specification of Letters Patent.

Patented Dec. 8, 1908.

Application filed January 2, 1906. Serial No. 294,810.

To all whom it may concern:

Be it known that I, BENJAMIN S. WARREN, a citizen of the United States of America, residing at Detroit, in the county of Wayne and 5 State of Michigan, have invented certain new and useful Improvements in Car-Roofs, of which the following is a specification, reference being had therein to the accompanying drawings.

10 The invention relates to new and useful improvements in car roofs, and consists in the construction of a car roof of sheet metal, which roof is adapted to have a longitudinally sliding motion on the car at the eaves, 15 with a spring or yielding connection between the roof and the car body, so that as the spring tends to resist this longitudinal movement it tends to return the roof to its original or initial position.

20 The invention further consists in the construction, arrangement and combination of the various parts, as more fully hereinafter described and particularly pointed out in the claims.

25 In the drawings, Figure 1 is a perspective view of a sheet which is of the kind I prefer to use embodying my invention; Fig. 2 is a perspective view of the eave portion of a car roof, showing the lower edges of the sheets 30 and the preferred manner of securing the sheets at the eave, my improved device not being illustrated therein; Fig. 3 is a vertical section through the eave portion of such a roof; Fig. 4 is a perspective view of the peak 35 portion of the roof, the caps which cover the corner joints being removed; Fig. 5 is a perspective view of one of the caps; Fig. 6 is a vertical section through the peak of the roof and through the cap in position; Fig. 7 is a 40 section through the roof beside one of the joints showing the preferred manner of making the spring connection between the roof and the car; Fig. 8 is an end elevation of Fig. 7; Fig. 9 is a cross-section on line x-x 45 of Fig. 7; Fig. 10 is a detached perspective view of the clip by means of which I connect the sheets to the car as shown in Figs. 7 and 8; Figs. 11 and 12 are perspective and plan views respectively of a modified form of this 50 connection; and Figs. 13 and 14 are perspective views of two other modifications of this connection.

At the present time there are two ways of connecting the so-called outside sheet metal 55 car roof in position upon the sheathing of the

car, one, and the usual way, being to lay the sheets, connected by joints, upon the sheathing and then to nail or otherwise secure the lower edge of the sheets to the side of the car. The other way is to lay the sheet-metal 60 sheets upon the sheathing and allow at the eaves a longitudinal motion of the sheets, the sheets being connected together in this construction with a flexible joint.

It has been found in the actual use of 65 cars that as they are coupled and as they travel over the road, particularly on curves, the car-frame yields, one side going forward and the other side going backward in relation to the center or ridge portion. When 70 the outer covering or sheet metal car roof is nailed to the car or secured so that it can have no longitudinal travel at the eaves, the result of this yielding of the car frame is to tear out the securing means, or if the securing means are applied at the joint, to cut off 75 or damage the joint at the eaves and thus cause the roof to leak. When the car roof is simply laid upon the sheathing and allowed to have substantially free longitudinal 80 movement at the eaves, it is found that the roof sheets will creep or travel at the edge and become distorted and seriously damaged. I overcome the objections to both these constructions by making a connection between 85 the car and the roof which is in the nature of a spring connection and which resists, while permitting, this longitudinal travel and tends to return the sheets to their original or normal position. It also properly distributes the travel at the eaves of the sheets 90 and makes each joint take up its proper amount of travel and thus prevents the distortion or buckling of the sheets.

The preferred form of roof to which I apply my invention comprises a sheet A, having the flexible joints B at opposite edges, this joint being substantially of the construction shown in Patent No. 655,941, to D. C. Ross, and consisting of interlocking inverted 95 involute hooks a, preferably terminating in abutting flanges b, as clearly shown in Fig. 9. At the lower edge this sheet preferably has the curved extension C, terminating in an inwardly and upturned hook C', this extension and hook being opposite the fascia D, of the car, and below the plane of the roof-sheathing E. At the upper edge the sheet 100 preferably has the upturned flange E'. The opposite upturned flanges of the sheets are 105 110

covered by an inverted U-shaped cap F, and at the joints are preferably covered by a joint cap F' which is secured to the roof by a bolt G, as shown in Fig. 6.

5 In order that the roof may be secured at the eaves free to have longitudinal motion, I secure to the fascia D preferably a series of hooks H (Fig. 3), which engage the hook C' of the sheet and act as the holding-down means for the eave portion thereof. The curved extension C is flexible and acts as a spring to take care of the expansion and contraction, and also any crosswise motion which the sheet may have upon the sheathing. With a roof thus constructed and having a free longitudinal movement of the eaves, as previously described, there is danger that one of the sheets will have more motion than the other, or that too great a motion will be imparted to the roof, causing buckling and damage to the sheets. In order to secure this roof so as to have a limited amount of longitudinal motion on the car and with the spring which will tend to return it to its normal position, I employ the clip I, shown in Fig. 10, as my preferred construction. This clip, in connection with this particular roof, consists of the plate c, which is adapted to be secured to the fascia of the car, the curved portion d which embraces the curved extension C of the roof sheet, and at its upper end it has the inwardly projecting pin e, which is of a size to engage within the joint and has a slot h adapted to engage the abutting flanges b of the two sheets, as shown in Figs. 7 and 9. When thus secured in position it is obvious that the sheets may have a longitudinal movement upon the car, and in such movement the clips I will remain stationary, the coiled joint surrounding the pin e of the clip will act as a spring or yielding connection between the sheet and the clip. For instance, if the roof tended to move to the left, it would assume the position shown in dotted lines at J, Fig. 9, and if it tended to move to the right there would be room for such movement in each joint and for each sheet. This is what I consider the preferred construction of roof sheet and connection to effect the result, and in this construction it will be observed that the yielding or spring connection is entirely in the joint or in a portion of the roof sheet. It is obvious, however, that the resilient feature may be embodied in the clip itself, or may be embodied partially in the clip and partially in the roof sheets, and also that it may be applied to other styles of roof sheets having other styles of joints, and some of these I have illustrated in Figs. 11 to 14.

In Figs. 11 and 12 I have shown the roof sheets J', one having a hook i and the other an upstanding flange k, forming an interlocked upstanding joint. I have shown a clip consisting of the securing portion or

plate l, with a spring arm m extending up beside the joint and having the bifurcated portion n engaging on opposite sides of the joint. In this construction the spring or yielding portion is entirely in the clip. In Fig. 13 I have shown a construction similar to that shown in Figs. 11 and 12, except that the clip has a lateral extension o above the top of the joint, and a saddle r engaging the joint.

In Fig. 14 I have shown a construction in which part of the yielding is effected in the roof joint and part by the clip, the clip in this construction consisting of a plate the same as l, and a spring arm m and a bifurcated portion n. Instead, however, of engaging on opposite sides of an upstanding joint, I have shown the joint formed and then bent into an inverted U-shape, which provides the yielding portion s with which the bifurcated portion n engages.

It is obvious that other forms of my invention may be devised, and that it may be applied to other forms of roof having other forms of joint; but so far as I know I am the first to construct a sheet metal roof which is free to have a motion longitudinally of the car at the eaves, with a yielding or flexible connection between the car and the roof.

What I claim as my invention is,—

1. The combination with a car, of a roof laid thereon free to move longitudinally of the car, and a flexible connection between the car and roof at the eaves resiliently resisting such longitudinal movement.

2. The combination with a car, of a roof laid thereon unsecured at the eaves against longitudinal motion, and a clip secured to the car and engaging the roof at the eaves, the construction being such that the connection between the car and roof resiliently resists but permits the eave portion of the roof to have a limited longitudinal motion.

3. The combination with a car, of an outside metal roof unsecured against longitudinal movement at the eaves, a bendable projection on the roof, and a clip secured to the car at the eaves engaging such projection so as to permit the bending thereof for the purpose described of yieldingly resisting the longitudinal movement thereof.

4. The combination with a car, of an outside metal roof having flexible involute rolled joints, of a clip secured to the car and engaging said joint so as to permit a limited movement of the roof sheets longitudinally of the car.

5. The combination with a car of an outside metal roof having flexible joints, said roof being free to have a movement longitudinally of the car, and a spring connection between the car and roof opposing such movement.

6. The combination with a car, an outside metal roof unsecured at the eaves against longitudinal movement, of clips secured to

- the car and engaging each sheet so as to permit and at the same time resiliently resist a limited movement of the sheets longitudinally of the car.
5. 7. The combination with a car, of an outside metal roof having joints between the sheets and clips secured to the car and engaging each joint, the parts being so constructed as to permit a limited longitudinal movement of each joint upon the car, and a spring acting to resist such movement and to return the sheets to their normal or initial position.
10. 8. The combination with a car of an outside metal roof having flexible joints, said roof being free to have movement longitudinally of the car, and a spring connection be-
15. tween each joint and the car opposing such movement.
9. The combination with a car, of an outside metal roof having joints, said roof being free to have movement longitudinally of the car and a spring connection between each sheet and the car opposing such movement.
10. The combination with a car of an outside metal roof thereon, having the joints terminating in the flanges, the clip having a slotted pin adapted to engage said flange.
20. 25. In testimony whereof I affix my signature in presence of two witnesses.

BENJAMIN S. WARREN.
